His Attorney.

UNITED STATES PATENT OFFICE.

EMILE J. GUAY, OF LYNN, MASSACHUSETTS, ASSIGNOR TO GENERAL ELECTRIC COMPANY, A CORPORATION OF NEW YORK.

ARC-LAMP.

1,276,522.

Specification of Letters Patent. Patented Aug. 20, 1918.

Application filed January 31, 1917. Serial No. 145,779.

To all whom it may concern:

Be it known that I, EMILE J. GUAY, a citizen of the United States, residing at Lynn, in the county of Essex, State of Massachusetts, have invented certain new and useful Improvements in Arc-Lamps, of which the following is a specification.

My invention has reference to alternating current arc lamps fed from a constant current supply system through the intermediary of a transformer, preferably an auto-transformer. The invention is especially useful in connection with arc lamps of the character known as luminous arc lamps, employing one metallic and one carbon electrode. In such lamps, and also in ordinary flame lamps it occurs or may occur that a film of insulating matter is formed at the arcing face of one or both electrodes, so that the starting of the arc, when the electrodes are cold, is difficult or uncertain with the normal arc voltage. In both kinds of lamp, but especially in luminous arc lamps, the arc is slender and is subject to fluctuations, due to the fact that at each reversal of current the arc has to start anew, sometimes from a comparatively hot and sometimes from a comparatively cold point of the respective electrode. The resistance of the arc may also vary suddenly within wide limits, and, therefore, being fed by a constant current, the difference of potential between the electrodes would vary suddenly within wide limits, especially when, by the consumption of the electrodes, the arc is lengthened. When this happens the maintenance of the arc by the energy supplied to it becomes uncertain and the arc is liable to collapse, and at such times it is necessary to bring the arc again to a stable condition. In the case of luminous arc lamps this is done by bringing the electrodes together and again reestablishing the normal arc. After this has been done, the old play begins again; that is to say, the arc again gradually becomes fluctuating and unsteady and, in the case of luminous arc lamps, it has to be extinguished and reestablished as before. Such, or similar operation, whereby the arc is restored to its normal length and condition, is called a feeding operation.

In accordance with my invention the feeding operation is induced by an electromagnet in a virtual or actual shunt around the arc, which shunt, however, is open be-

fore the arc is established and is only closed by the establishment of the arc and is then not sufficiently energized to induce a feeding operation until the arc becomes unduly long, fluctuating and unsteady and diverts a high potential to the shunt magnet. By the use of such shunt magnet which is on open circuit before the arc is established the secondary of the transformer through which current is supplied to the electrodes can attain a higher difference of potential than if the electromagnet were in a constantly closed shunt and this extraordinary high potential serves to break through any insulating film that may have formed between the electrode faces, whereby the initial starting of the arc is insured. All this will more fully appear from the following detailed description with reference to the accompanying drawing in which Figure 1 is a skeleton view of a luminous arc lamp embodying my invention and Fig. 2 is a diagram of a modification thereof.

Referring now particularly to Fig. 1, the lower electrode 1 is the metallic electrode of a luminous arc lamp, preferably made of titanium carbid, such as is produced in an arc furnace and which contains an excess of titanium. The upper electrode 2 is here shown as made of carbon. These two electrodes with their holders are here shown as connected through a chain 3, or other flexible medium which passes over a sheave 4, which is journaled on a lever 5, which is fulcrumed at 5', and which at one end is connected with the armature 6, of the series electromagnet 7, and at the other end with the barrel of a dash-pot 8, the piston 9 of which is fixed to some part of the frame of the lamp. The weights of the upper and lower electrodes and of their holders and appurtenances are so proportioned that the upper electrode, even when largely consumed preponderates, so that when the sheave is free to rotate the two electrodes will come together.

Lamps of this character are designed to be focusing lamps and when fed by alternating currents the electrodes, if both are of the same material, are consumed about equally; but since in the case here shown the upper electrode is made of carbon, it will consume faster than the lower electrode and it is therefore given a larger diameter than the lower electrode, so that

about equal lengths of both electrodes will be consumed. For this reason the flexible connection 3 between the two electrodes is here shown as passing over the same sheave. If the two electrodes had equal diameters the flexible connection from the upper electrode would be secured to a sheave of somewhat larger diameter than the flexible connection from the lower electrode. These are matters well understood in the art and need not be here dwelt upon.

On the lever 5 is pivoted a brake shoe 10, the bearing face of which is adapted to engage the inner surface of the projecting rim 11 of the sheave. In consequence of this construction, when the armature of the electromagnet 7 is raised the brake shoe clamps the sheave, which is thus partially rotated to separate the electrodes. When, on the other hand, the armature of the electromagnet 7 descends, as it will when there is no current through the magnet coil, the brake shoe releases the sheave and the electrodes are free to come together by the preponderance of the weight of the upper electrode and its holder.

On the left-hand side of the lever 5, between the sheave 4 and the barrel 8 of the dash-pot, there is adjustably secured an eccentric 12, from which a spur 13 extends downwardly in such position that when the left side of the lever 5 descends, this spur will bear upon a strip 14 extending from a contact 15, which is fixed to some stationary part of the lamp frame.

The electromagnet 16 has a core or armature 17, which, when there is no current through the magnet winding is in the lowest position shown in the drawing; it carries a movable contact 18 just below and in alignment with the fixed contact 15. If the electromagnet 16 is sufficiently energized its core or armature will rise and the contact 18 rising with it will bear upon the fixed contact 15.

The circuit connections are as follows: The constant current line terminals 19, 20 are connected with the primary 21 of a step-up transformer, the secondary 22 of which is connected at one end with one terminal of the series magnet winding 7 by conductor 23 and at the other end with the lower electrode holder by conductor 24. The other terminal of the electromagnet winding 7 is connected with the upper electrode holder by a conductor 25. The line is also connected on one side by conductor 26 to the eccentric 12 and at the other side by conductor 27 with one terminal of the electromagnet winding 16, the other terminal of which is connected by conductor 28, with the stationary contact 15. In addition to this, there is a cross-connection between the movable contact 18 and the conductor 27 by a conductor 29.

The operation of a lamp thus equipped is as follows: When there is no current on the lamp the electrodes are in contact, as shown in the drawing, and there may or may not be an insulating film on one or both electrode faces, and if there is such a film the secondary of the transformer is on open circuit. At this stage the magnet 16 is also on open circuit, since the spur 13 of the eccentric 12 is out of contact with the strip 14. Now when current is turned on to the lamp from a constant current supply, a high difference of potential is established between the terminals of the secondary of the transformer and between the electrodes. This difference of potential is greater than would be the case if the circuit of the electromagnet 16 which actually shunts the primary and virtually shunts the secondary of the transformer were closed, and this potential is exceptionally high when there is an insulating film between the electrode faces. Therefore, a high potential discharge between the electrodes passes and breaks through any insulation which may there exist. The current now flows through the electromagnet 7, the armature or core 6 of which is thereby raised, and the right-hand end of the lever 5 is elevated, whereby the brake shoe 10, gripping the rim of the sheave 4 rotates the latter counter-clockwise, whereby the electrodes are separated and the arc is established. Toward the end of this movement the spur 13 comes into contact with the strip 14 and thereby closes the circuit through the shunt magnet 16 as follows:

From line 19 by conductor 27 to and through electromagnet 16, by conductor 28, contact 15, strip 14 to spur 13 of eccentric 12, and by conductor 26 to line 20. At this time the arc has its normal length and the transformer is fully loaded; therefore, the potential difference between the line terminals is comparatively small. The winding of electromagnet 16 is so designed that under these normal conditions it receives insufficient current to raise its core. The lamp, therefore, continues to operate, starting with a normal arc, which, however, by consumption of the electrodes, becomes eventually unsteady and fluctuating and the difference of potential between the line terminals becomes high enough to pass through the electromagnet 16 sufficient current to raise its core 17 and to establish contact between the movable contact 18 and the fixed contact 15. As soon as this happens the current is diverted from the magnet 16 by the short-circuiting conductor 29, and this not only actually short-circuits the magnet 16, but also the primary of the transformer and thereby virtually short circuits the arc and the arc establishing magnet. The lamp is thereby deprived of current, the arc breaks,

the electromagnet 7 is deenergized, its core drops and by the downward movement of the lever 5 at the right-hand end the brake shoe 10 releases the rim 11 of the sheave 4, 5 so that the latter is now free to rotate and the electrodes come together. The next instant, however, the arc is again established as before. It will thus be seen that by the attainment of a high difference of potential 10 between the line terminals, when the arc becomes too long or for any other reason, the short circuiting of this shunt magnet induces a feeding operation which, in the construction here shown, consists in extinguishing the arc by a short circuit and reestablishing the same to normal condition; the magnet 16, therefore, controls the feeding 15 of the electrodes.

The circuit connections may be varied 20 without deviating from my invention in several ways, one of which is diagrammatically indicated in Fig. 2, where all the parts are supposed to be the same as those shown in Fig. 1, except that the feed control magnet 16 is in a shunt around the secondary of the transformer and the short circuit around the control magnet is also in a shunt to the secondary of the transformer.

An ordinary transformer may be used, 30 but the drawing shows the preferable form, namely an auto-transformer.

It will now be understood that this invention is applicable to all alternating current arc lamps in which unduly high voltage 35 peaks may occur, no matter whether these high voltage peaks be due to the nature of the electrodes employed or to other causes.

It will also be understood that the ultimate effect upon the operation of the lamp 40 is the same whether the shunts and short-circuits herein referred to are actual or virtual shunts and short-circuits, so that the terms shunt and short-circuit in the appended claims have the generic significance.

45 What I claim as new and desire to secure by Letters Patent of the United States is:

1. The method of operating an arc lamp from a constant alternating current line, which consists in momentarily inducing by 50 the line current a sufficiently high potential discharge between the contacting electrodes to puncture any intervening insulating film and separating the electrodes to establish the arc, then and thereby partially short-circuiting the electrodes and reducing the voltage 55 between them to that requisite to maintain a normal length of arc, and dead short-circuiting the electrodes and thereby causing a feeding operation when an unduly high voltage 60 age peak occurs.

2. The method of operating arc lamps from a constant alternating current line through the medium of a step-up transformer, which consists in charging the primary 65 of the transformer with the full line

current and thereby inducing in the secondary circuit and between the contacting electrodes a sufficiently high potential discharge to puncture any intervening insulating film and separating the electrodes to establish the 70 arc, then and thereby reducing the primary charge and the arc voltage to that suitable to maintain a normal length of arc, and dead short-circuiting the primary and thereby causing a feeding operation when an unduly 75 high voltage peak occurs.

3. An arc lamp for an alternating constant current supply line, comprising a step-up transformer the primary of which is in the line and the secondary in the electrode 80 circuit, an arc establishing magnet in the electrode circuit, a normally open circuited feed control magnet subjected to variations of potential corresponding to those in the electrode circuit, means actuated by the arc 85 establishing magnet for closing the circuit of the feed control magnet, and means for short-circuiting the control magnet in response to an unduly high potential discharge through the same.

4. An arc lamp for an alternating constant current supply line, comprising a step-up transformer the primary of which is in the line and the secondary in the electrode 90 circuit, an arc establishing magnet in the electrode circuit, a magnet in a normally open shunt across the primary of the transformer, means actuated by the arc establishing magnet for closing the shunt circuit, and means for short-circuiting the primary of 100 the transformer in response to an unduly high potential discharge through the shunt magnet.

5. An alternating current arc lamp having electrodes which always tend to and which are in contact when there is no current through the lamp; a step-up transformer, the primary of which is in a constant current supply circuit, and the secondary of which is in the electrode circuit; a series electromagnet in the electrode circuit for establishing the arc by the energy conveyed by the secondary of the transformer; a shunt magnet, the circuit of which is normally open; means for closing the shunt circuit by 105 the arc establishing means, and means for inducing through the shunt magnet an electrode feeding operation by the series magnet when an unduly high voltage peak occurs at the arc.

6. An alternating current arc lamp having electrodes which always tend to and which are in contact when there is no current through the lamp; a step-up transformer, the primary of which is in a constant current 110 supply circuit and the secondary of which is in the electrode circuit; a series electromagnet in the electrode circuit for establishing the arc by the energy conveyed by the secondary of the transformer; a shunt magnet 115 120

the circuit of which is normally open; means for closing the shunt circuit by the arc establishing means; means for short-circuiting the transformer by the shunt magnet when 5 an unduly high voltage peak occurs at the arc and thereby deenergizing the series magnet and allowing the electrodes to come into

contact, whereby the initial condition of the lamp is restored and the arc is reestablished to normal length.

10

In witness whereof I have hereunto set my hand this 29th day of January, 1917.

EMILE J. GUAY.
